UNITED STATES PATENT OFFICE.

ROBERT E. DANIELS, OF YOUNGSTOWN, OHIO.

DESIGN FOR A CORNER-PROTECTOR STRIP.

SPECIFICATION forming part of Design No. 28,509, dated April 26, 1898.

Application filed April 5, 1897. Serial No. 630,876. Term of patent 14 years.

To all whom it may concern:

Be it known that I, ROBERT E. DANIELS, a citizen of the United States, residing at Youngstown, in the county of Mahoning and State of Ohio, have invented a new and original Design for a Corner-Protector Strip for Walls, of which the following is a specification.

This invention relates to a new and original design for a corner-protector strip for walls; and it has for its object to provide a design of this character that shall be both useful and ornamental.

The leading feature of the design resides in a straight flat plate formed with a longitudinal series of rounded openings and provided at one edge with a plurality of laterally-deflected approximately T-shaped flange projections, said flange projections extending alternately in opposite directions and being disposed at an obtuse angle to the body of the plate.

In the drawings, Figure 1 is a perspective view of a corner-protector strip embodying the herein-described design. Fig. 2 is a

side view thereof. Fig. 3 is a rear edge view 25 thereof.

Referring to the drawings, the numeral 1 designates a straight flat plate formed with a longitudinal series of rounded openings 2. The rounded openings 2 are of a circular form, 30 and in addition to said openings the plate is further provided at one edge with a plurality of approximately T-shaped flange projections 3. The flange projections 3 extend alternately in opposite directions from one edge of the 35 plate 1 and are disposed at an obtuse angle to the body of the plate.

What I claim is—

The design for a corner-protector strip for walls, herein shown and described. 40

In testimony that I claim the foregoing as my own I have hereto affixed my signature in the presence of two witnesses.

ROBERT E. DANIELS.
